UNITED STATES PATENT OFFICE.

ADOLF SCHEUFELEN AND FRITZ SCHUMACHER, OF OBERLENNINGEN-TECK, GERMANY, ASSIGNORS TO THE FIRM ERSTE DEUTSCHE KUNSTDRUCK-PAPIERFABRIK CARL SCHEUFELEN, OF OBERLENNINGEN-TECK, GERMANY.

METHOD OF CUTTING NARROW STRIPS FROM A ROLLER OF CELLULOSE MATERIAL.

No Drawing.

Application filed May 12, 1921. Serial No. 468,964.

To all whom it may concern:

Be it known that we, Dr. ADOLF SCHEUFELEN and FRITZ SCHUMACHER, citizens of the German Republic, residing at Oberlenning-
5 ingen-Teck, in the State of Wurttemberg, Germany, have invented certain new and useful Improvements in a Method of Cutting Narrow Strips from a Roller of Cellulose Material, of which the following is
10 a specification.

Our invention relates to an improved method of cutting narrow strips from a roller of cellulose-material, for the purpose of twisting said strips into a yarn qualified for
15 being spun. Said method consists in passing a blade through the rolled up sheet of cellulose-material as it is delivered from the paper-machine, and the particular feature of novelty of our invention resides in draining
20 said roll of cellulose-material, before rolling up the same, only to that degree, as is required for the subsequent spinning of the said strips.

We are aware that it is known to cut a
25 narrow strip from a roll of cellulose-material by a blade passing through the said roll and that it is also known to, make undergo the said roll first a process of complete drying and then to wet the roll before cutting the
30 same into strips. But it has been found by experience, that a thread prepared by such method does not at all resist moisture for any length of time. Besides, it is not

economical first to waste a good deal of heat in drying the material and then to restore a certain degree of the moisture.

According to our invention, the wet sheet of cellulose-material, as it comes from the wet-press, or from a drying-cylinder of a sifting-cloth or a dandy-roller of a coarse-drying-machine is only subjected to a draining process which leaves sufficient moisture as is required for the subsequent spinning process of the strips. The wet sheet is either rolled up in its full width or is divided into several sheets if the width is inconvenient. The cutting-process is preferably performed by a thin circular blade rotating with great speed, while the rolled up sheet slowly turns. But the circular blade can
45 of course be an endless, flexible blade like a ribbon-saw or by a reciprocating blade, below which the roll to be cut is revolved, with great speed.

What we claim is:

The method herein described which consists in partially drying a whole sheet of cellulose material, leaving therein the required amount of moisture, then rolling up the said sheet and finally cutting the rolled
60 up sheet into narrow strips.

In testimony whereof we have affixed our signatures.

DR. ADOLF SCHEUFELEN.
FRITZ SCHUMACHER.
